UNITED STATES PATENT OFFICE.

WILLIAM E. SHEEHAN, OF ALBANY, NEW YORK.

ROLLER FOR PAPER-MAKING MACHINES AND PROCESS OF MANUFACTURING SAID ROLLERS.

No. 882,351.

Specification of Letters Patent. Patented March 17, 1908.

Application filed January 15, 1906. Serial No. 296,174.

To all whom it may concern:

Be it known that I, WILLIAM E. SHEEHAN, a citizen of the United States, residing at Albany, in the county of Albany and State of New York, have invented certain new and useful Improvements in Rollers for Paper-Making Machines and Processes of Manufacturing said Rollers; and I do hereby declare the following to be a full, clear, and exact description of the invention, such as will enable others skilled in the art to which it appertains to make and use the same.

This invention relates to the structure and manufacture of rollers used in paper making machines and particularly to couch-rolls of the sort used on a Fourdrinier paper making machine and to press-rolls used in other paper making machines.

The objects of the invention are: (1) to so construct these rollers that they shall be homogeneous and therefore capable of holding their proper cylindrical form and surface and, if damaged, be capable of presenting a new and perfect surface when turned down in a lathe: (2) to so construct these rollers that they may be renewed or replaced at the mill, where in use, instead of having to be sent to the manufacturer: (3) to provide rollers which shall have the requisite elasticity and still be capable of retaining the desired true and even surface: and (4) to provide rollers which, in the expense of manufacture, economy in use and perfection in operation, shall excel those now generally known.

With the attainment of these objects in view, the invention consists in the roller constructed and in the mode of construction practically as herein described and claimed.

To assist in the disclosure of this invention, reference is made to the accompanying drawings wherein:

Figures 1 and 3 represent, in side elevation, rollers involving my invention, but varying in the arrangement of material from which they are made: Figs. 2 and 4 are respectively transverse sections of said rollers: Figs. 5 and 6 show in perspective two stages in the formation of the roller seen in Fig. 3: Figs. 7, 8, 9, 10, and 11 represent different steps in one mode of formation by which the roller in Fig. 1 may be produced.

It is well known that, of all natural fibers, none possess lasting resilience in a greater

degree than does wool and this resilience is still manifest when this fiber is compacted in a mass under great pressure. Other fibers soon mat under heavy and continual pressure whereas wool does not. Rollers heretofore made from cotton and from felt are wanting in resilience at the outset and soon lose what little they had.

By making rollers, for the purpose specified, from carded wool and in the manner herein set forth a more perfect and enduring result is obtained than heretofore known.

The fibers of wool are always kinky and interlace more or less no matter in what manner the wool may be carded. This interlacing is more pronounced when the wool is taken from the card in sheets than when it issues from the carding machine in ribbons or rolls, but it may be used in either form in carrying out this invention.

In forming the roller seen in Fig. 1, the wool is taken from the card in sheets and cut into rings or washers and threaded upon the shaft. They are then subjected to hydraulic pressure axially applied until compacted to the desired degree. In building up the roll on its own shaft, these washers are threaded on in batches and pressed down successively until the roller is completed. By applying steam heat during the operation the wool, because of its crawling nature when subjected to heat, comes together in a mass and adheres to the shaft.

The wool may be applied to the shaft in ribbons, as suggested in Fig. 5, by wrapping it in successive turns about the shaft. The portion thus applied to the shaft may then be subjected to hydraulic pressure and produce a washer or section such as seen in Fig. 6. In a roller thus constructed the general direction, or lay, of the fibers is concentric about the roller substantially as shown in Figs. 3-6; while in a roller constructed from rings or washers cut out of a sheet of carded wool (Figs. 1 and 2) the fibers lie in all directions intermixed and interlaced.

As above described, the rollers may be built up on their own shafts. It is, however, preferable to build the rollers, or rather the bodies of the rollers, in sections, so that when required these sections may be shipped to the paper mills and there slipped onto the roller shaft, thereby enabling a mill to renew a roller with but little delay.

Sections constructed as in Figs. 5 and 6 may be so used. It is preferable, however, to construct the sections substantially as illustrated in Figs. 7-10. For this purpose, 5 rings or washers cut from sheets of carded wool are preferably used. These are slipped onto a core 12 in sufficient number to produce, when pressed down to the desired density, a section of about one inch in thickness. 10 Sections thus produced will hold their forms fairly well, but it is preferable to fortify them against change in form by cementing together the fibers of the inner portions of the sections. This may be done by injecting, 15 into this portion of the hollow cylinder of fibers, some suitable agglutinating substance or cement either before pressure is applied or when the mass has been partially compressed. This may be done in various ways. 20 One practical way is by making the core 12 hollow and perforating it and injecting the cement through the perforations into the wool to the desired extent. It is preferable to compress the wool partially before 25 injecting the cement and to apply this preliminary pressure axially to the outer peripheral portion of the cylindrical mass of wool, then to inject the cement to about one third the radial thickness of the mass, (substantially as indicated by the darker portion 30 13), then after the cement has become nearly hard to apply the pressure to the inner portion as well and reduce the whole to the desired size and condition substantially as indicated in Figs. 9 and 10. These sections 35 may then be threaded upon a roller shaft, as 14, and clamped snugly together by the usual washers and nuts 15 and 16. The interior diameter of the sections is made 40 slightly smaller than the shaft so that the sections when forced onto the shaft will cling thereto. The slight bulging of the wool at the outer or uncemented portion 17, of the sections (exaggerated in the drawings) 45 provides for said sections fitting so snugly together upon the shaft that no meeting line between them is discernible. This fitting together of the sections is also so perfect as to make the entire fibrous portion of the 50 roller as solid as though it were one continuous section.

In the formation of sections for composite rollers just described other fibrous material than wool may be used, provided it be such as can be readily cemented together substantially as specified.

The sections made in any of the above ways may be put into a lathe and turned down to the desired diameter, or the roller 60 when built up of them or built up as first described, may be turned down to the desired extent and, should the surface of a roller become filled up and hard or be damaged in any way so as to mark the paper, it 65 may be resurfaced by turning it down. In a

roller built up of sections, should a section be seriously damaged or prove defective it may be readily replaced by a new section.

Cement, or other means for making the inner portion of a section integral may be 70 applied in like manner to a roller having a continuous fibrous body and also to sections made up of flat or round ribbons or slivers of wood or other fibrous material. These and other modifications in structure and process 75 of manufacture may obviously be made within the scope of this invention.

Pounded felt, which has heretofore been used for the construction of couch rolls, is 80 made of fiber taken from goods submitted to treatment and rendered comparatively inelastic, and inclined to assume and maintain a form or position without responding to any particular spring or elasticity tending to restore its particles after pressure has been 85 applied to it. In other words, the fiber of the material of which the pounded felt is composed becomes "set" after being operated upon. This is because of the treatment to which the material is subjected, in order 90 to make it pounded felt the wool is submitted to pounding in a tub containing steam, soap and hot water, and while in this tub heavy wooden blocks hung upon a crank or a knob fall upon this mass of wool fiber 95 until it becomes, by the soap and water and the friction generated by the pressure from these blocks falling upon it, a mass in which the character of the fiber is changed and it is set in a rigid condition.

The material of which carded wool rollers are constructed differs from the material used in pounded felt rollers, in that it retains the life, spring and elasticity. The wool, when it is operated upon immediately after 105 its removal from a sheep is elastic, full of vitality and thoroughly qualified for use, and after it is carded it is rather improved, and the particles are kinky, resisting any tendency to fold them and tending to resume the former position.

The invention claimed is:—

1. A couch roller for paper making machines, consisting of a shaft surrounded by carded wool compressed into a dense elastic, 115 homogeneous mass and turned down into cylindrical form.

2. A couch roller for paper making machines, consisting of a shaft surrounded by layers of carded wool wrapped in successive 120 turns about the shaft and compressed and turned down into a dense, elastic, cylindrical mass.

3. A couch roller for paper making machines, consisting of a shaft surrounded by 125 fibrous material treated at its inner portion about the shaft, with an agglutinating substance, whereby said portion is made a rigid mass and thereby retains the fibrous material in proper form.

4. A couch roller for paper making machines, consisting of a shaft having clamped thereon several disks of compressed fibrous material each treated, at its inner portion about the shaft, with an agglutinating substance whereby said portion is made a rigid mass and retains the disk in proper form.
5. A disk for composite couch rollers in paper making machines, consisting of compressed fibrous material treated, at its inner portion about the shaft, with an agglutinating substance whereby said portion is made rigid and thereby retains the material in its compressed form.
- 15 6. The process of making disks or sections for composite rollers consisting in placing fibrous material about a core, impregnating the inner portion of said material about the core with a cement, firmly compressing said material and holding it under pressure until the cement hardens.
7. The process of making disks or sections for composite rollers, consisting in wrapping layers of fibrous material about a perforated 25 core, injecting a cement into the portion thereof adjacent to the core, compressing
- said material and holding it in compressed form until the cement hardens.
8. The process of making disks or sections for composite rollers, consisting in placing a cylindrical mass of fibrous material about a suitable core, applying pressure axially to said mass at its outer peripheral portion, injecting cement into its inner peripheral portion, allowing the cement to become nearly hard and then applying axial pressure to the inner peripheral portion until the cement becomes hard.
9. A perforated disk or washer for composite couch rollers, consisting of firmly compressed fibrous material held rigidly together at its inner peripheral portion.
10. A centrally perforated disk for composite couch rollers, consisting of carded wool impregnated throughout its inner peripheral portion with cement.

In testimony whereof, I affix my signature, in presence of two witnesses.

WILLIAM E. SHEEHAN.
